DESIGN FOR A FLASK

Martin H. Donahoe, Jr., West Conshohocken, Pa.

Application May 31, 1939, Serial No. 85,267

Term of patent 3½ years

To all whom it may concern:

Be it known that I, Martin H. Donahoe, Jr., a citizen of the United States of America, residing at West Conshohocken, in the county of Montgomery and State of Pennsylvania, have invented a new, original, and ornamental Design for Flasks, of which the following is a specification, reference being had to the accompanying drawing, forming part thereof.

On the drawing:

Fig. I represents a plan view of a flask showing my new design;

Fig. II represents a front view of said flask;
Fig. III represents an enlarged front view of said flask with its case opened.

Fig. IV represents an enlarged side elevation of said flask with its case opened.

For convenience of illustration, only a fragmentary portion of the carrying strap for the flask has been shown.

I claim:

The ornamental design for a flask, as shown and described.

MARTIN H. DONAHOE, JR.
